U.S. Appl. No. 29/559,270, filed Mar. 25, 2016; Unknown.

Primary Examiner — Austin Murphy*(74) Attorney, Agent, or Firm* — Sterne, Kessler, Goldstein & Fox P.L.L.C.(57) **CLAIM**

The ornamental design for a retail display, as shown and described.

DESCRIPTION

FIG. 1 is a top front perspective view of a retail display showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the retail display that form no part of the claimed design.

1 Claim, 5 Drawing Sheets---
